CLAIM

I claim the ornamental design for a lip balm dispenser, as shown and described.

DESCRIPTION

FIG. 1 is a perspective of my new design for a lip balm dispenser, showing the lip balm dispenser in a closed configuration;

FIG. 2 is a front view thereof;

FIG. 3 is a rear view thereof;

FIG. 4 is a left side view thereof;

FIG. 5 is a right side thereof;

FIG. 6 is a top view thereof;

FIG. 7 is a bottom view thereof; and

FIG. 8 is a perspective of my new design for a lip balm dispenser, showing the lip balm dispenser in an open configuration having a top and a bottom;

FIG. 9 is a front view of the bottom;

FIG. 10 is a rear view thereof;

FIG. 11 is a left side view thereof;

FIG. 12 is a right side thereof;

FIG. 13 is a top view thereof; and

FIG. 14 is a bottom view thereof.

FIGS. 9-14 illustrate the bottom with the lid removed for convenience of illustration.

1 Claim, 14 Drawing Sheets
